UNITED STATES PATENT OFFICE.

CHARLES EDWARD LEE, OF FRANKLIN, MANITOBA, CANADA, ASSIGNOR TO ROY JOHN STEWART, OF FRANKLIN, MANITOBA, CANADA.

NUT-LOCK.

1,188,664.

Specification of Letters Patent. Patented June 27, 1916.

Application filed August 2, 1915. Serial No. 43,271.

To all whom it may concern:

Be it known that I, CHARLES EDWARD LEE, a subject of the King of Great Britain, residing at Franklin, Province of Manitoba, 5 Canada, have invented certain new and useful Improvements in Nut-Locks; and I do hereby declare that the following is a full, clear, and exact description of the invention, such as will enable others skilled in 10 the art to which it appertains to make and use the same:

The invention to be hereinafter described relates to nut locks.

In order to more clearly disclose the construction, operation, and use of the invention, reference should be had to the accompanying drawings forming part of the present application.

Throughout the several figures of the 20 drawings like reference characters designate the same parts.

In the drawings: Figure 1 is a front perspective view of the special angle plate used; Fig. 2 is a front view of the lock 25 plate; and Fig. 3 is an end view of the same.

The main objects of the invention are to provide an efficient and durable nut lock specially adapted for use in connection with railways and which can be produced at a 30 very low cost. These and other objects are accomplished by the invention to be described.

Referring to the drawings in detail, the angle plate 1 is provided with a plurality 35 of vertical openings having V tops and surrounded by similarly shaped outwardly projecting flanges 2. At each upper corner of plate 1 a gravity hook 3 is pivotally mounted.

40 The side plates 4 are placed in position, in the usual manner, and secured by the bolts 5 inserted through the rail webs and the side plates, and the nuts 6 threaded on

the outer ends thereof. When the nuts have been tightened the angle plate 1 is placed 45 in position so that the flanges 2 surround several sides of the nuts and prevent turning of the same.

The hooks 3 pass across the ends of the outer side plate 4 and the angle plate, and 50 engage behind the side plate. This effectively prevents lateral movement or displacement of the angle plate which is secured by spikes in the usual manner, in the event of the securing spikes working loose. This nut lock- 55 ing angle plate can be readily and easily applied to railroads already constructed by simply pulling the spikes.

It is thought that the construction, operation, and use of the invention will be clear 60 from the preceding detailed description.

Changes may be made in the construction, arrangement, and disposition of the several parts of the invention without in any way departing from the field and scope of the 65 same, and it is meant to include all such within this application wherein only a preferred form has been disclosed.

Having thus fully described my invention, what I claim as new and desire to secure by Letters Patent is:

A nut lock comprising a plate having openings therein, a flanged plate having slots therein coincident with the openings and provided with flanges around the slots, 75 and gravity hooks pivotally secured adjacent the ends of the flanged plate to engage behind the first plate and to permit a pivotal movement upward to clear the ends of both plates.

In witness whereof I have hereunto set my hand in the presence of two witnesses.

CHARLES EDWARD LEE.
